UNITED STATES PATENT OFFICE.

WALTER C. HEYMANN, OF OAK PARK, ILLINOIS.

INTERNAL-COMBUSTION ENGINE.

1,403,245.

Specification of Letters Patent. Patented Jan. 10, 1922.

Application filed February 9, 1920. Serial No. 357,206.

To all whom it may concern:

Be it known that I, WALTER C. HEYMANN, a citizen of the United States, residing at Oak Park, in the county of Cook and State 5 of Illinois, have invented new and useful Improvements in Internal-Combustion Engines, of which the following is a specification.

This invention relates to internal-combustion engines of the four cycle type, having a reciprocating piston, and its object is to provide in an engine of this type a piston having a variable stroke, the explosion or working stroke being longer than the intake 15 or charging stroke.

A further object of the invention is to make the exhaust stroke of equal duration and length of travel as the explosion stroke thereby insuring a complete scavenging of 20 the cylinder.

The objects stated are attained by means of a novel combination and arrangement of parts to be hereinafter described and claimed, and in order that the same may be 25 better understood, reference is had to the accompanying drawings forming a part of this specification.

In the drawings, Figure 1 is a plan view of the engine; Fig. 2 is a side elevation there- 30 of; Figs. 3 to 7 are diagrams illustrating the operation of the engine, and Fig. 8 is an enlarged detail view of the piston structure, partly in section and broken away.

Referring specifically to the drawings, 35 denotes the cylinder of the engine, the same being supported on standards 11. The drawings show a stationary engine, the cylinder being horizontally positioned, but it will be understood that the invention is also 40 applicable to vertical as well as to portable engines. The cylinder is shown as considerably longer than the cylinder of an ordinary engine, in view of the greater length of the explosion or working stroke obtained, 45 the cylinder length depending on the desired length of the stroke.

In the cylinder 10 operates a reciprocating piston consisting of two members 12 and 13, respectively which are so connected that 50 they are movable relative to each other. The piston member 12 is a solid one, having a grooved exterior as usual for rings. The piston member 13 is hollow and in alignment with the member 12, ahead of the 55 latter.

The rear end of the hollow piston mem-

ber 13 is closed by a head 14 having dash-pot chambers 15 and 16, respectively, in its sides. The forward end of the piston member 13 has a bearing 17 for a pin 18 whereby 60 connection is made with a pair of connecting rods 19 extending rearwardly and having their outer ends connected to wrist pins 20 on flywheels 21 mounted on the drive shaft 22, whereby the motion of the piston is 65 transmitted to said shaft.

From the forward end of the piston member 12 extends a rod 23 which passes slidably through an opening in the head 14, and has at its outer end an abutment in the form 70 of a plunger 24 adapted to enter the dash-pot chamber 16. On the forward end of the piston member 12 is a similar plunger 25 adapted to enter the dash-pot chamber 15. The plungers 24 and 25 are provided 75 with the usual spring-seated relief valves 26.

The two piston members 12 and 13 slide back and forth in the cylinder 10, and they are also slidably relative to each other. When the firing or working stroke takes 80 place, the member 12 abuts against the rear end of the member 13, the plunger 25 having entered the dash-pot chamber 15, as shown in Fig. 3. Both piston members now make a maximum stroke and travel together. 85 Fig. 4 shows the end of the firing stroke and the beginning of the exhaust stroke. On the exhaust stroke, the two piston members again travel together and make a stroke of the same length as the firing stroke, thereby 90 insuring complete scavenging of the cylinder 10. When the piston member 13 again advances for the next stroke, it separates from the piston member 12, and the latter remains stationary until the inner end of 95 the head 14 strikes the plunger 24 and the latter enters the dash-pot chamber 16, as shown in Fig. 5. When this occurs, the piston member 12 is drawn forward by its rod 23 and it travels forward with the piston member 13 to the end of the forward stroke 100 of the latter as shown in Fig. 6. This movement of the piston member 12 is the suction stroke. On the next stroke, the piston member 13 moves rearwardly and the head 14 105 leaves the plunger 24. Before the end of this rearward stroke of the piston member 13, its head 14 engages the plunger 25, the latter entering the dash-pot chamber 15 as shown in Fig. 7. The piston member 12 now 110 travels rearwardly with the piston member 13 and makes a compression stroke, and as

the two pistons are now again together, they are ready for the next firing stroke. The dash-pots afford a cushion so that the piston members are not violently jarred when they 5 become connected.

It will be evident from the foregoing that the piston member 12 operates as the working piston of the engine, whereas the piston member 13 operates to transmit the motion 10 thereof during its firing stroke, and transmits motion thereto for its exhaust, intake and compression strokes.

By the piston structure hereinbefore described, the length of the firing or working 15 stroke of an engine may be increased without increasing the intake or charging stroke, with the result that the efficiency of the engine is materially increased without an increase in the fuel consumption. Assuming that the length of the intake stroke is 20 three inches, and the length of the firing stroke is twenty-four inches, the engine will consume from seventy-five to eighty-five per cent of the fuel charge, resulting in an increased efficiency of sixty per cent. The 25 advantage of the engine will therefore be apparent when it is remembered that the efficiency of an ordinary internal combustion engine is only sixteen to twenty-five 30 per cent. The diagram shows a piston design by which a firing stroke of approximately twice the length of the intake and compression strokes is obtained.

The intake and exhaust valve mechanism 35 need not be described as it forms no part of the present invention, the same being readily applicable to engines of standard type and design.

I claim:

40 1. In an internal combustion engine, a cylinder, a reciprocatory piston working in the cylinder, a rod extending forwardly

from said piston and having longitudinally spaced abutments, a motion transmitting and imparting member slidably mounted 45 in the cylinder ahead of the piston and having a head through which the aforesaid rod slidably passes to locate one of the abutments in front of said head and the other abutment to the rear of the head, a crank 50 shaft, and an operative connection between the aforesaid member and the crank shaft, the rear abutment being in contact with the head during the entire firing stroke of the 55 piston and transmitting the motion of the latter to the aforesaid member, and said abutment remaining in contact with said head during the next or return stroke of the member imparted thereto by the crank shaft, whereby the piston is given an exhaust 60 stroke equal to the length of the firing stroke, whereas during the suction stroke the motion transmitting and imparting member moves away from the piston to separate the head from the rear abutment, 65 said head thereafter coming in contact with the forward abutment to impart a suction stroke to the piston, and said head separating from the forward abutment on the next or rearward stroke of the member and thereafter coming in contact with the rear abutment to impart a compression stroke to the 70 piston, the length of such suction and compression strokes being less than the length of the firing and the exhaust strokes of the 75 piston.

2. An internal combustion engine according to claim 1, in which the abutments are plungers, and the sides of the head have dash-pot chambers adapted to seat said 80 plungers.

In testimony whereof I affix my signature.

WALTER C. HEYMANN.
